COMMINUTOR OR CUTTER

Edwin L. Beekman, Middletown, N. J.

Application January 28, 1932. Serial No. 589,508

6 Claims. (Cl. 146—166)

This invention relates to comminutors or cutters for apples or like fruits or vegetables and more particularly to improvements in devices of this character which are more especially useful for reducing apples to small particles forming a mass or cake which subsequently may be subjected to pressure by any suitable means in order to express the juice.

It is usual to reduce apples to a finely comminutive state before the pressing operation is performed since the amount of juice procured from an apple is largely dependent upon the thoroughness of the preliminary comminuting. It is common practice to perform this preliminary comminution by means of rotary cutters or spreaders of various descriptions. A disadvantage usually present in devices of this character heretofore known is the danger of the operator's hand being injured by the rotating cutting element.

An object of the present invention is to provide an efficient comminuting device in which the arrangement of parts is such that the danger of the operators being injured is eliminated or reduced to a minimum.

Among the other objects of the invention is to provide a device of the character described of simple construction and which may be taken apart easily for cleaning purposes and the cutting edges or knives of which are self-sharpening.

Further objects of the invention will become apparent from a reading of the following detailed description, the appended claims and the accompanying drawing.

35 In the drawing:

Figure 1 is a perspective view of a comminuting device constructed in accordance with the invention;

40 Figure 2 is a longitudinal vertical sectional view of the device shown in Figure 1;

Figure 3 is a view in end elevation of outer and inner conical members comprising the cutting elements of my improved device; and

45 Figure 4 is a transverse sectional view showing two conical members in contacting relation.

The device comprising the present invention may be mounted advantageously on top of a cider press or the like provided with means adapted to receive the comminuted fruit or vegetable particles discharged, but since such press constitutes no part of the present invention, an illustrative embodiment generally designated A is shown as being mounted upon a base B, such as a table top or the like.

55 The comminuting device A shown in the draw-

ing includes a pair of cooperating conical members comprising an outer conical member 1 and an inner conical member 2. The outer member 1 is provided at its apex with a hollow sleeve bearing 3 extending axially of the member 1, the sleeve bearing 3 being externally threaded as at 4 for connection with the internally threaded end portion 5 of a horizontally disposed hollow shaft 6 journalled in a bearing bracket 7 secured to the base B.

Any suitable means may be provided for rotating the outer conical member 1 and for the purposes of illustration I have shown an electric motor 8 connected by means of a belt 9 to a pulley 10 secured to the hollow shaft 6.

In accordance with the invention means are provided for mounting the outer conical member 1 and the inner conical member 2 in coaxial relation and for both relative rotary and sliding movements. To this end the inner member 2 is provided with an axial stem 11 which extends from the apex of the inner member and which has a long uninterrupted bearing surface adapted to fit slidably and relatively rotatably in the bearing sleeve 3 of the outer member 1. In operation 80 of my device it is desirable that the inner conical member be held against rotation and for this reason I preferably extend the stem 11 through the base end of the inner conical member and provide this extended part of the stem with a 85 handle 12 which is securely fixed to the stem, a web 13 extending inwardly from the inner sides of the inner conical member for connection with the rearwardly extending part of the stem 11 serving to provide a rigid assembly of the stem 90 and inner conical member.

The end of the stem 11 which is adapted to be inserted in the bearing sleeve 3 is preferably pointed as at 14 in order that the stem more effectively may pierce an apple to be cut or comminuted. In operation the apple is pierced and positioned on the stem in contact with the apex end of the inner conical member as illustrated in Figure 1. The stem 11 is then inserted in the bearing sleeve 3 of the outer conical member and 100 by means of the handle 12 the inner conical member is then moved inwardly axially of the outer member and the apple pressed against the inner surface of the rotating outer conical member 1. In order effectively to reduce the apple to small 105 particles the conical members are provided with cooperating cutting means. An important feature of the invention is the provision in the rotary outer conical member of a plurality of staggered elongated depressed portions 15, each of which 110

may preferably be curved as shown in Figures 3 and 4. These depressed portions are adapted to cooperate with a plurality of staggered raised knife edges 16 bounding cut-out portions of the inner conical member 2 to cut and reduce to small particles a piece of fruit ground between the conical members. As will be clear from an inspection of Figure 3 of the drawing the knife edges are curved in a direction oppositely to the curvature of the depressions in the outer conical member, that is the depressions in the outer conical member and the knife edges on the inner member are reversely curved so that when the two members are brought into actual contact as shown in Figure 4 there will be a wiping or honing action on the knife edges which maintains the latter sharp.

From the foregoing it will be understood that the outer member 1 is the only rotating part of my device. In operation the operator holds the inner conical member against rotary movements by means of the handle 12 and exerts sufficient pressure inwardly to cause the fruit to be cut between the two conical members. The inner member and stem 11 are then completely withdrawn and another piece of fruit placed upon the stem 11 preparatory to being cut. It is clear that since the only knife elements, namely the knife edges 16, are carried by the non-rotary conical member 2, the danger of the operator's hand being cut is eliminated. The rotary outer conical member 1 contains no sharp edges which would be likely to cause injury even if the operator's persons accidentally should come in contact with the member 1. Other advantages of my device are its extreme simplicity and the ease with which it may be cleaned.

Although the particular device illustrated and described is considered to embody the invention in a practical form it will be understood that various changes may be made in the construction and relative arrangement of the parts without departing from the spirit of the invention as defined in the appended claims.

45 I claim:

1. In a device of the character described, the combination of a rotatably driven outer conical member, an axial bearing at the apex of said

member, an inner cooperating conical member, and an axial stem fixed to said inner member and extending from the apex thereof and fitting slidably in said bearing.

2. In a device of the character described, the combination of an outer conical member provided at its apex with an axially disposed bearing, means outside of said member connected to said bearing for supporting and rotating said member, an inner cooperating conical member, and an axial stem fixed to said inner member and extending from the apex thereof and fitting slidably in said bearing. 80

3. In a device of the character described, the combination of a rotatably driven outer conical member, an axial bearing at the apex of said member, an inner cooperating conical member, and an axial stem fixed to said inner member and extending from the apex thereof and being adapted to be removably supported in said bearing. 90

4. In a device of the character described, the combination of a rotatably driven outer conical member, a cooperating inner conical member, means mounting said member in coaxial relation and providing for relative axial movement therebetween, an elongated depression in the inner surface of the outer member, and a co-operating knife edge on said inner member. 100

5. In a device of the character described, the combination of a rotatably driven outer conical member, a cooperating inner conical member, means mounting said members in coaxial relation and providing for relative axial movement therebetween, a curved depression in the inner surface of the outer member, and a reversely curved cooperating knife edge on said inner member. 110

6. In a device of the character described, the combination of a rotatably driven outer conical member, a cooperating inner conical member, means mounting said members in coaxial relation and providing for relative axial movement therebetween, a plurality of staggered curved depressions in the inner surface of the outer member, and a plurality of staggered reversely curved knife edges on said inner member. 125
